WINDING METHOD AND MACHINE

Waldo H. Zander, Brookville, Fred D. Zander, Dayton, and Delbert I. Wilson, Tipp City, Ohio, assignors to McGraw Electric Company, Elgin, Ill., a corporation of Delaware

Application September 29, 1950, Serial No. 186,476

47 Claims. (Cl. 242—9)

This invention relates to wire heating coils of the flat type having straight windings all located on one face of a flat form and anchored by notched edges of the form, such as are commonly employed as heating elements in electric toasters. The invention includes both a new winding method for making the coils and a winding machine operating according to the method.

The single heating face flat coils described have heretofore been wound by hand by a slow, two-handed technique involving awkward manipulation in anchoring the wire at the notched edges of the flat form of sheet mica or other insulating material. Usually flat resistance wire ribbon is employed for the coils, and, because of its flat shape, inherent stiffness and resilience, it is difficult to manipulate, particularly at the anchoring points and, further, it tends to accidental twisting in the course of winding. For these reasons winding of the ribbon from a supply roll heretofore has been impractical and the practice has been to use cut lengths of ribbon for winding the single heating face coils.

A primary object of the invention is to provide an improved winding method for the described flat heating coils with single heating faces adapted to ribbon and other shapes of wire involving a new technique for obtaining proper engagement of the wire with the notched edges of the supporting forms.

Another object of the invention is to provide a method of winding flat heating coils with single heating faces according to which the wire is wound from front to back through an edge notch of a flat form, drawn to a surplus length at the back of the form then directed forwardly to form a large loop in the surplus length and drawn to the front of the form through an adjacent notch to contract the loop into tight engagement with the back of the form between the notches.

Another object of the invention is to provide a method of winding flat coils with single heating faces from wire ribbon with local twists in the ribbon at the anchoring notches on the forms. It is found that such twists serve to provide tight engagement of the ribbon with the notched edges.

A further object of the invention is to provide a method of winding the described flat coils of wire ribbon which avoids twisting of the ribbon along its supply path and adapted to supply the ribbon from rolls of any size. According to the method the ribbon is held against twisting in the course of feeding, but drawn through one edge notch of the flat form to a surplus length at the back of the form and then manipulated forwardly without twisting and drawn through the next notch to the front of the form to cause a local twist to develop in the ribbon against the back of the form between the notches.

Another object of the invention is to provide a new method for winding flat coils on a mounted flat form with a wire feeding holder by effecting oscillating arcuate winding movement about a fixed axis of one of such

2

members relative to the other and moving one of such members also along a feed path lengthwise.

Another object of the invention is to provide a new method for winding single faced flat coils employing mechanical wire manipulating and guiding devices for effecting tight anchoring of the wire at the notched edges of a flat form and for locating the wire in the notches.

Another object of the invention is to provide a new method of winding the described flat heating coils employing coil holding and wire handling mechanical devices adapted for relative winding and feeding movements which can be effected through power mechanism or by manual manipulation of the devices.

Another primary object of the invention is to provide a winding machine for mechanically winding heating coils on one face of flat forms.

Another object of the invention is to provide a machine for winding coils on flat forms having variations in the spacing of the anchoring notches in the form edges.

Another object of the invention is to provide a coil winding machine embodying power operated oscillating coil winding mechanism and power operated feed mechanism.

Another object of the invention is to provide a power operated flat coil winding machine adapted to high speed production of coils.

Still another object of the invention is to provide an automatically operated and controlled flat coil winding machine.

Still another object of the invention is to provide for the winding of electric heating elements with single heating faces suitable for electric toasters.

Both the inventive method and machine and their advantages may be understood by reference to the accompanying drawings and the detailed description thereof to follow.

In the drawings:

A partially completed heating element of the type to be produced according to the invention is shown in Fig. 30, the same comprising a mica or other suitable insulating flat form EF wound on one face with successive windings of electrical resistance wire ribbon R. The ribbon windings are anchored along opposite edges of the form by passing from the front side of the form through notches N and held at the back side by supporting legs L, as best shown in Fig. 31.

The heating element is shown in Fig. 30 supported for winding with its notched side edges horizontal, and with its bottom vertical at the right. The winding of the ribbon is shown as being progressive from bottom to top. As conventionally, the windings are relatively close together near the bottom of the form and their spacing increases in the direction of the top of the form, located at the left. Such variable spacing is accomplished by increasing the spacing of notches N along the edges.

Supporting form EF for winding according to the new method illustrated in Figs. 1 to 16 is flat form

holder FH comprising a rigid plate adapted to support the back of the somewhat flexible mica form and provide reinforcement therefor during winding. As shown in Fig. 4, such holder is narrower than the heating element form EF so that the notched side edges of the form are spaced outwardly at the lengthwise horizontal edges of the holder.

The form is removably retained on form holder FH in any suitable manner. We prefer to provide V-shaped retaining notches in the opposite edges of the form located at the ends of the holder to engage retaining fingers on the holder. In Fig. 2 the edge of the form at the right engages the inner end of raised portion 50 on the holder from which projects inwardly a V-shaped retaining finger 51 interfitting with one of the form notches.

The wire ribbon R is fed from a ribbon holder RH comprising interfitting grooved and ribbon feed rolls 52 and 53. Winding on form EF is accomplished by oscillating either the ribbon holder RH or the form holder FH relative to the other about a fixed axis. Preferably, and as shown, the form holder is the oscillating member, being suitably supported to oscillate about its horizontal medial axis. The ribbon holder is supported in fixed spaced relation to such axis a short distance outwardly of the arcuate path of oscillation about such axis of the ribbon notches N of the horizontally extending edges of the heating element form EF mounted on the form holder FH. The alternative procedure comprehended within the new method of oscillating the ribbon holder while supporting the form holder against turning is feasible.

The preferred mounting of the form holder FH for oscillatory turning movement about its axis and relative to the ribbon holder may be accomplished in any suitable manner, one example of which is illustrated in Figs. 28 to 30, later to be described. Since the winding of the ribbon progressively along form EF is of some distance there must be a relative feed movement in an axial direction of either the form holder or the ribbon holder RH. As the preferred alternative, the ribbon holder is suitably mounted for such feed movement axially.

In a simple adaptation of the new method the feed movement just referred to can be effected manually without the aid of mechanical guides. It is further preferred to provide guides to bring the ribbon into registry with the notches N of the heating element form, such guides being mounted for feed movement along the edges of the form simultaneously with the ribbon holder RH and oscillating with the form and form holder FH in the course of winding. A similar pair of such ribbon guides RG and RG' are variously shown in Figs. 1-16 as embracing the opposite horizontally extending notched edges of the form EF.

Ribbon guide RG provides a channel of V-shape and open at its bottom adapted to guide the ribbon into successive form notches when the ribbon is wound from front to back and also when the winding is from back to front. This ribbon guide has a bottom recess accommodating the notched edges of the form and the thickness of the ribbon at both faces of the form. An undercut and/or groove parallel to the edge of the form to accommodate the thickness of the ribbon between notches at the back of the form is provided in the guide and adjoins the main recess. In the particular forms shown part 55 of the guide is of generally triangular shape with a sloping face defining one side of the channel. Such part is undercut at the front to overlie the edge of the form as is shown in Figs. 2 and 4. At the other side of the channel is a front plate 56 undercut to accommodate the thickness of the form and of the ribbon at the front of the form, as shown in Figs. 1 and 6 and having a sloping inner edge bounding the channel. Such edge is rounded in its lower portion. Back of the plate facing the channel is a sloping faced part 57 terminating in a

rounded lower end as shown in Fig. 5 above the lower area of the form notches. Parts 56 and 57 are secured on a supporting part 58 mounted on a common base 59 with part 55 on the opposite side of the channel as shown in Fig. 4.

The second guide RG' is similar in construction to guide RG. While not so shown, except in figures hereafter to be described, guides RG and RG' are rigidly interconnected for common feed movement along the opposite notched side edges of form and are alined for correct registry with the opposite form notches. It is also to be understood that ribbon holder RH is mounted to move with the guides and in vertical alinement with the channels therein.

In Fig. 1 form holder FH is shown in its starting position tilted on its axis relative to ribbon holder RH. The ribbon has been secured in any suitable manner to the lower edge of form EF. The form holder is now turned forwardly to the position shown in Fig. 3 to wind ribbon R across the front of the form and through guide RG into the first notch. The parts are shown in their relative position at the end of such movement in Figs. 2, 3 and 4, form holder FH now being reversely tilted relative to the ribbon holder at one extremity of its path of oscillatory movement. It will be observed that a substantial length of ribbon has been drawn between the edge of the form and the ribbon holder.

The ribbon holder is again turned clockwise from the position shown in Fig. 3 in continuous movement through the position shown in Figs. 7, 9 and 12 to the opposite limit of its oscillatory path as shown in Fig. 13. In the position shown in Fig. 3 or shortly after such movement has begun the ribbon guides and ribbon holder are advanced along the form into alinement with the next pair of notches at opposite side edges of the form. The guide is shown in partially advanced position in Fig. 5 and is in registry with the next notch in Fig. 8. When movement has reached the position shown in Fig. 7 the length of ribbon previously drawn assumed the form of a large slack loop which is readily guided by part 57 of the guide into the next notch N. In the position shown in Figs. 9 and 10 the slack loop has been drawn down into close engagement with the back of the leg portion of the form intervening between the first two notches as will be understood from Fig. 11. Continuing through the position shown in Fig. 12 the second winding of ribbon is laid across the front of form EH. By the time it has reached its second limit position shown in Fig. 13 the ribbon has been guided by ribbon guide RG' into the notch in the second side edge of the form. In reaching the position shown in Fig. 13 also a length of ribbon has been drawn between the second edge of the form and ribbon holder RH similar to that shown in Fig. 3.

The next movement of the form is in a counterclockwise direction from the position shown in Fig. 13 through the positions shown in Figs. 14 and 15 to a tilted stop position, shown in Fig. 16 which is the same as the starting position shown in Fig. 1. In the position shown in Fig. 13 or shortly after movement therefrom has started ribbon guides RG and RG' and ribbon holder RH are advanced to the third notch along the form EF. The large slack loop which has been formed from the excess length of ribbon as shown in Fig. 14 is readily guided by guide RG' into the third notch at the second edge of the form by the time the form has turned to the position shown in Fig. 15 and the excess loop has been drawn tightly against the back of the leg portion of the form between the second and third notches. Further turning movement to position 16 merely completes the first winding cycle in which two lengths of ribbon have been laid across the front of the form and anchored at the backs of the opposite notched side edges. The cycle is repeated by the oscillatory turning movement of the form and the advance of the ribbon guides and the ribbon holder from notch to notch is repeated, as will be under-

stood from Fig. 30 until the desired number of windings have been put on the form.

By reference to Figs. 11 and 31 it will be observed that a twist has been formed in the ribbon at the back 5 of the form between the notches. This is considered desirable in securing tight engagement of the ribbon with the form and results from the fact that the ribbon holder holds the ribbon against twisting but a twist is necessarily formed as the loop shown in Figs. 7 and 14 10 is drawn against the back of the form. It may be noted that the twists formed at the opposite notched side edges of the form are in reverse directions, this being due to the difference in the directions of movement of the form relative to the ribbon holder.

The oscillating winding cycle just described is further explained in Fig. 38 wherein the movements of the form holder FH are illustrated. Line A represents the starting and stopping position of the form holder as in Figs. 1 and 16. Line B represents the first limit position of the 15 path of movement as in Fig. 3 and line E represents the second limit position of such path. The three stages of movement of the form holder are: first, counterclockwise from A to B; and, second, clockwise from B through line D, corresponding to Fig. 12, to E; and, third, again counterclockwise from E back to A.

Points a, b, c, d and e represent the points of engagement of the ribbon with the edges of the form in the position represented by lines A, B, C, D, E. Thus the ribbon is anchored in the first notch of the second edge 20 of the form in starting position A, such anchoring having been done manually. At b the ribbon is at the first edge, having been drawn from front to back through the first notch in such edge in the initial movement of the form holder from A to B. At points c and d the ribbon is still at the first edge but by the time it reaches 25 D it is in the second notch thereof. At point e, the ribbon is again at the second stage of the form since while the first edge moved from D to E below the ribbon has been drawn from front to back through the second notch in the second edge in the corresponding movement of the second edge from B (Fig. 12) to A (Fig. 13) at the top.

Line C is directly below the position of the ribbon holder RH. Line F is likewise, with a 180° arc between C and F. Not only must the first limit position at B be at an angle to C but in such position the form holder must be sufficiently inclined to the ribbon holder RH that the ribbon is drawn well down into the notch in the first edge and extends backwardly to the ribbon holder at an abrupt angle (see Fig. 3) clear of interfering with the subsequent advance of the ribbon guide RG to the second notch. Similar considerations apply to the location of the second limit position at E when the ribbon extends backwardly through the notch in the second edge and ribbon guide RG' is ready for advance (see Fig. 13).

The actual angles of the limit position at B beyond C and of limit position E beyond F are not critical and depend in part upon the distance between the location 60 of ribbon holder RH and the form. By way of example, angles in the range of 30° to 40° have proved satisfactory. With such angles beyond 180° the form will oscillate through an overall arcuate path in the range of 240° to 260°.

The method which has been described for winding flat heating elements with single heating faces can be carried out by manually turning the form holder FH and by manually advancing the ribbon guides RG and RG' and the ribbon holder RH from notch to notch along the 65 form EF. As so practiced the method is a marked advance over prior hand winding since the hands are not required to manipulate the ribbon at any stage of winding and merely anchor it to the heating element form at the start of winding and severing the ribbon after winding has been completed.

Further, the method is adaptable to power, and the invention further includes a motor operated machine for winding the heat element according to the method.

The machine

The general construction of the machine is shown in Figs. 17, 18 and 19. In the specific form to be described the machine operates to wind electric heating elements with twenty windings of varying spacing on a single heating face and suitable for electric toasters. Since two windings, in opposite directions can be obtained with each complete oscillatory winding cycle, and with feed advance each half cycle, according to the description of the new method in connection with Figs. 1 to 16 and as depicted in the oscillatory path diagram of Fig. 38, such a heating element will require ten cycles and twenty notch by notch feed advances.

Before proceeding with the detailed description of the machine the main features will be pointed out by reference to the schematic view of Fig. 27. The form holder FH is mounted for oscillation on its long terminal medial line as an axis relative to the ribbon feeding holder RH by electric motor EM through a rotary to oscillatory motion translating drive. The ribbon guides RG and RG' are oscillated in the same manner but are mounted independently of the form holder together with the ribbon holder RH, by a feed carriage FC for feed advance along the axis of the form holder. Advance of the feed carriage is controlled by a rotary cam drum CD having twenty cam steps of varying dimension conforming to the changing spacing of the notches along the edges of the coil forms (see Fig. 30) so that the feed carriage advances notch by notch along each side edge of the form each half oscillating cycle of the form holder to provide exact registry of the ribbon guides and the ribbon holder with the notches.

Cam drum CD is also driven by electric motor EM, through a rotary speed reducing drive to make one complete revolution for each complete coil winding operation of ten oscillating cycles of the form holder, such rotary drive being in a 1:10 ratio to the oscillating drive of the form holder.

The advance of the feed carriage FC, ribbon guides RG and RG' and ribbon holder RH is effected under control of the cam drum by a separate motor, pneumatic motor PM.

Through an appropriate automatic control circuit each heating element may be wound in a continuous operation and the machine reset and then stopped for replacement of the completed heating element by a new form for winding.

The specific machine operation just mentioned is merely exemplary. The invention involves the machine in its basic construction, since the same may be adapted to produce coils on flat forms of any desired size and with any desired number of windings for electric toasters, or for other uses.

In the description to follow some structural details, such as various bearings, are omitted from mention where they are unimportant to a proper understanding of the inventive machine.

The form holder

The holder FH, as best shown in Figs. 20, 26, 28 and 29, comprises a solid rigid plate, as in Fig. 1, adapted to support a heating element form for winding. At one end the plate is provided with an extension 600 of reduced width to which is secured a stub shaft 61 having a bearing journal in a supporting post 62 upstanding from the right end of the machine casing CS.

Rigid with the other end of the form holder is a hub 63 split longitudinally on one side and threaded, and clamped by a screw through its split side (see Fig. 25), rigidly to the end portion of a long oscillatable drive shaft 64 which extends lengthwise of the machine. Shafts 64

and 61 have a common axis extending along the medial line of form FH.

The opposite end of shaft 64 is journaled in the inner end wall 65 of the upstanding portion of the casing at the left end of the machine. Near its end the shaft has an integral flange 66, and threaded on the shaft near the flange is a nut 67. Bearing 68, secured in wall 65 by a flanged retaining ring 69 is clamped between the shaft flange and the nut to support shaft 64 against axial movement.

Form locking mechanism

A readily releasable mechanism is provided which will lock a form on the form holder in proper position for winding and which is quickly adjustable to facilitate withdrawal and replacement of a form after winding. Referring first to Figs. 28 and 29, together with Fig. 25, on extension 600 of form holder FH is a raised element 50 adapted to engage one edge of a form and provided with a projecting retaining finger 51 in the same manner as in the form holder shown in Fig. 2 and adapted, as earlier explained, to engage a retaining V-shaped notch provided in the form for the purpose.

At the opposite end of the form holder is a retractable undercut bar 70 forming with the surface of the form holder a slot adapted to receive the opposite edge of a form and having a retaining finger 71 adapted to engage a further V-shaped form notch. A rectangular opening 72 in the form holder slidably mounts a flat extension 73 of a hub 74. Bar 70 is secured to the hub extension at the front face of the form holder. A plate 75 is secured to the hub extension to slidably engage the back of the form holder and hold bar 70 against the form holder. Hub 74 is independent of hub 63 and is designed for movement lengthwise of the form to move bar 70 between locking and retracted positions relative to a form on the holder.

The form holder oscillating shaft 63 is hollow and through it extends a slidable shaft 76 anchored to hub 74. The opposite end of shaft 76 extends beyond shaft 63, as seen in Figs. 25, 27, 20 and 21, and through a bore in a cylinder 77 into a larger counterbore. A bearing 79 is adapted to journal shaft 76 for turning oscillation with shaft 63 without turning movement of cylinder 77. End portion 78 of shaft 76 is of reduced diameter, providing a shoulder, and a nut 80 is threaded to hold the bearing against the shoulder. Bearing 79 is secured in the cylinder counterbore so that the cylinder and shaft are adapted to conjoint axial movement.

Cylinder 77 is mounted for axial movement in bore 81 of an interior boss 82 integral with the casing. A cross-bore 84 extends inwardly from the front casing wall to meet bore 81 and terminates beyond in a reduced inner end portion 85. Housed in the cross-bore is a shaft 86 housing an integral gear 87 coacting with ratchet teeth 88 on the underside of cylinder 77. The outer end portion 89 of the shaft is reduced to provide a shoulder which engages a retaining ring 90 supported by a removable cover plate 91 and holding the shaft against axial movement. A lever 92 is secured to the projecting reduced shaft portion 89 at the outside of the casing.

Turning of lever 92 results in axial movement of cylinder 77, shaft 76, hub 74 and form locking bar 70. Turning of the lever in one direction moves bar 70 inwardly lengthwise on the form holder FH to lock a form on the holder in contact with element 50 and fingers 51 and 71. Reverse turning of the lever retracts the locking bar to free a form for removal from the holder.

Oscillating form holder drive

The form holder FH is oscillated in its winding path by a drive from motor EM shown in Fig. 27. Only portions of such drive are shown in Fig. 20 for reasons of clarity but the portions omitted therein are shown in Figs. 21 and 22.

Through reduction gearing 100 the motor drives

sprocket 101 having a chain drive 111 to sprocket 102 mounted on shaft 103 adjacent the enlarged shaft portion 105 which journals the shaft in casing boss 104. A conventional clutch connection is provided between hub 106 of sprocket 102 and the shaft. Hub 107 is splined on shaft 103 for axial movement and has a clutch tooth 108 in clutching engagement with a coacting recess in the hub 106 of sprocket 102 in the position shown in Fig. 20. Hub 107 mounts a hand wheel 109. A smaller wheel 110 has threaded connection (not shown) with the shaft and is interconnected with wheel hub 106 for free turning movement relative thereto on the shaft and common axial movement. By turning wheel 110 hub 106 is moved to the left on the shaft to free the clutch connection with sprocket 102. The shaft is then free of driving connection with the sprocket. Under such conditions the shaft and parts of the machine driven thereby can be manually turned through wheel 109.

Gear 112 fixed to shaft 103 drives through an intermediate gear 113 on stub shaft 114 to a gear 115 on stub shaft 116. The shafts and latter two gears are supported by boss 104 as shown in Figs. 21 and 22. A rotary to oscillating motion drive is provided between gear 115 and drive shaft 64 of the form holder. This includes an eccentric pin 117 projecting from gear 115 mounting a slide block 118 spaced from the gear by a retaining disc 119 fixed to the eccentric pin. A bell crank 120 is journalled by bearing 121 on shaft 122, which shaft is supported by boss 104 and a further boss 123 on the right upper casing wall 124. Bell crank 120 has a lower bifurcated arm 125 in slot 126 of which eccentric slide block 118 is slidable and from which it is held from displacement by retaining disc 119 and by end plate 127 which bridges the lower ends of the crank arm. Rotation of gear 113 is thus translated into oscillating motion of bell crank 120. The other arm 128 of the bell crank 120 is provided at its end with an arc of rack teeth 129 meshing with a gear 130 fixed to the end of form holder shaft 103.

It will be apparent that by proper arrangement of the parts of the eccentric drive just described shaft 103 can be caused to oscillate form holder FH in an arcuate path having any desired limits. The arrangement is such as to conform to limits shown in and explained in connection with Figs. 2 and 13 in the range of 240° to 260°. The starting and stopping position of the form holder at an intermediate portion of its path is determined by the starting and stopping time of motor EM and requires no special arrangement of the eccentric drive.

Wind advance assembly

Mechanism is provided for advancing the ribbon intermittently along a form being wound in timed relation. There are two intermittent advances for each complete oscillating cycle, or one advance for each wind in each of the opposite winding directions.

The advance mechanism shifts after the ribbon has been wound from front to back of the form through a notch at on side edge of the form so that on the reverse wind from back to front the mechanism will cause the ribbon to wind through another notch along the same side edge, and the mechanism again shifts for the similar operation at the opposite side edge of the form.

The combination of means for effecting an oscillating wind of ribbon in opposite directions on one face of a form and means for effecting intermittent advance of the ribbon along the form in time relation with the winds in each direction constitutes a broadly new operating combination for flat coil winding within the scope of the invention. It will be apparent that the winding advance may be of either the ribbon feed along a form or of a form relative to a fixed position of ribbon feed.

The particular machine under description is to be understood as merely one preferred embodiment of the invention. The same, as already pointed out, mounts the

form to be wound for oscillation by a form holder in fixed position. Accordingly, mechanism is provided for advancing the ribbon feed along the form.

5 A feed carriage FC is mounted on the machine for movement in a straight path parallel to the axis of oscillation of the form holder FH, to effect wind advance of the ribbon feed along the form holder. This is shown best in Figs. 20, 23 and 28 as comprising a housing 139 mounted on a base 140. The carriage is ball bearing mounted. Ball bearing track bars 141 and 142 are secured to opposite sides of carriage base 140 and coacting opposing ball bearing track bars 143 and 144 are mounted on and lengthwise of the machine casing. The bearings are contained by complementary channels or pockets in the opposing sides of each pair of bars, as shown in Fig. 23, and the carriage base is supported clear of the top surface of the machine casing for easy movement lengthwise of the form holder.

20 Through housing 139 of the feed carriage extends the oscillating drive shaft 64 for form holder FH and actuating rod 76 of the form release mechanism which is housed within such shaft. Shaft 64 is surrounded by a sleeve 151 journaled by bearings in housing 139.

The feed carriage mounts a horizontally extending arm 25 145 secured to housing 139 and at its outer end supporting ribbon feed holder RH in vertical alinement, or substantially so, with the axis of form holder FH and, preferably, at a relatively short distance above the arcuate path of the side edges of a form EF mounted in winding position by the form holder. As earlier pointed out, such distance influences the selection of the limit positions of the oscillatory path of the form holder.

30 Movement of the feed carriage FC along its track on the machine casing will advance the ribbon feed holder RH along the forms. It also can be employed to advance further devices connected with the ribbon feed, as hereinafter pointed out.

Ribbon guiding assembly

40 Ribbon guides RG and RG' desirably are provided to cooperate with the ribbon feed holder RH in effecting winding through the notches at the opposite edges of the form. Their utility arises from the fact that the ribbon feed holder RH is spaced from the form during every 45 oscillating winding cycle, and at varying distances. It is desirable, therefore, to control the ribbon in close proximity to the notched side edges of the form. The ribbon guides serve this function.

45 While the ribbon guides RG and RG' serve to guide the ribbon into notches at the side edges of the form on winds from front to back, when the ribbon is under tension, their desirability is even greater on winds through notches from back to front of the form when the ribbon is not under tension and a slack loop is in the ribbon 55 between the form and the ribbon feed holder RH as a result of a reversal in direction of wind. By proper construction of the ribbon guides such slack loop can be controlled and the slack eliminated on the wind from back to front of the form and the ribbon can be guided into the proper notches.

60 The ribbon guides shift with the ribbon holder RH along the form from notch to notch by having a separate mounting which permits them to oscillate with the form holder FH.

65 The ribbon guides are mounted by feed carriage FC for oscillation in the winding path and shift along the form by a mounting as shown in Figs. 20 and 27 and in the more detailed views of Figs. 26, 28 and 29. A yoke Y is mounted on the feed carriage FC, the same 70 having a hub 150. Embracing oscillating shaft 64 of the form holder is a sleeve 151, already briefly mentioned, which extends through the feed carriage and is provided with a flanged end portion secured to yoke hub 150. Such sleeve rides in bearings in the feed carriage and, as shown in Figs. 20 and 27 is provided with a threaded

nut 153 which coacts with the flange and bearings to support yoke Y for shifting movement with the feed carriage. As shown in Fig. 20 shaft 64 is provided with a spline 152 and sleeve 151 is initially formed to engage such spline so that the yoke as well as the form holder are oscillated by the shaft.

Arm 154 of the yoke extends lengthwise of the form holder and terminates in a boss 155 at its outer end, upon which ribbon guide RG is mounted, as best shown in Fig. 28. A second arm 156 of the yoke is similarly disposed on the opposite side of the form holder and terminates in an end boss 157, upon which ribbon guide RG' is mounted.

Also secured to bosses 155 and 157 and interconnecting yoke arms 154 and 156 is a cross frame 158, shown in Figs. 26 and 28. Mounted on such frame are a pair of rollers 159 and 160 which ride along track rails 161 and 162 formed on the back side of form holder FH. Through this arrangement the ribbon guides RG and RG' are supported in fixed relation to the winding position of a form on the form holder and for shifting movement lengthwise along the form holder.

The construction of the ribbon guides RG and RG' is similar to those shown in Figs. 1 to 16 illustrating the winding method. Referring to Figs. 26, 28 and 29 and to the further detailed views of Figs. 40 and 42, ribbon guide RG includes ribbon guiding part 55 of generally triangular shape with a sloping face defining one side of a channel, and such part is undercut at its front end to overlie the edge of the form. Located opposite part 55 is a front plate 56 having an undercut or recess 173 in its lower portion adapted to receive the edge of a form. Such plate has an inclined edge complementary to sloping surface of part 55. The lower end thereof is rounded and located in spaced relation to the lower end of part 55 to define between them a narrow groove through which ribbon is guided into notches of the form. Extending rearwardly from plate 56 is a rearwardly and upwardly sloping part 57 terminating in a rounded lower end. Part 57 is secured to upstanding support 58 which is mounted by a base 59. The base is provided with a top insert 170 upon which support 58 is mounted with the under edge of part 57 spaced above the top surface of the insert, as shown in Fig. 41. The latter arrangement permits ribbon after a winding from front to back through one form notch to ride beneath part 57 when the ribbon guide assembly is shifted along the form. At the next notch on a reverse winding from back to front the ribbon is guided downwardly along the part 57 and off the rounded lower end thereof into the new notch.

Front plate 56 is preferably hinged at its upper end to support 58 by a hinge pin 171. A spring 172 tends to maintain the plate against the front faces of the support and part 57 but permits the plate to swing outwardly in case of ribbon winding difficulties.

A horizontal groove 60 is provided in the front face of support 58 to accommodate the thickness of ribbon wound between two notches at the back of the form in winding advance of the ribbon guide assembly by the feed carriage FC. A similar groove 60' is provided in the front face of the raised portion at the left of base 59 beneath the part 55 for accommodating the thickness of the ribbon between the notches at the back of the form so that the feed carriage can be returned to starting position without withdrawal of a wound form from form holder FH.

Ribbon guide RG' is constructed similarly to ribbon guide RG except that the positions of the various parts are reversed so that corresponding parts of the two holders are aligned with each other on opposite sides of form holder FH, as best shown in Fig. 28.

The cooperative relation of ribbon guides RG and RG' with ribbon holder RH in providing registry of the ribbon with the form notches is shown in Figs. 30 and 32. In Fig. 30 ribbon R has been guided into a notch at one side

of the form by ribbon guide RG' on a wind from back to front when the ribbon is under tension to be guided into a notch in the second side edge of the form from guide RG. In Fig. 32 the ribbon is shown passing from front to back of the form and the direction of the wind of the form has been reversed in its oscillatory path so that a slack loop forms in the ribbon. Such loop is accommodated by ribbon guide RG and will be guided in through the appropriate notch upon the next wind from back to front.

The shift of the feed carriage to advance both ribbon holder RH and ribbon guides RG and RG' along the form must be controlled. The mechanism for such purpose will now be described.

15 *Advance assembly shift control*

The feed carriage FC and other parts of the ribbon advance assembly are shifted intermittently in timed relation with the oscillating wind of the form holder under control of rotary cam drum CD. Such cam drum and its operation are shown in Figs. 20 and 27 and the cam development of the cutout cylindrical surface of the drum is shown in Fig. 37.

20 The cam formation is a series of steps beginning with top step 180 through a progression of intermediate steps 181 and ending with bottom step 182. The series extends spirally about the drum in one complete revolution. The depth of the cam step in the direction of rotation of the drum determines the amount of winding shift of the ribbon advance assembly lengthwise of the axis of the form holder and such depth is determined by the spacing of the notches along the side edges of any form to be wound. As has been mentioned, the usual heating element has notch and wind spacing which increases from a close spacing at the bottom area of the form, usually at spaced points along the form, to a considerably wider spacing at and adjacent the top of the form. (See, again, Fig. 30.) To provide for such winding, the cam steps of the drum are made shallower at the top area of the cam surface and are increased in depth at step intervals, the deepest steps being in the area of the finishing end of advance.

25 The width of the steps is the same so that the time interval of advance remains constant. From this it might appear that the advances would occur when the form holder reaches the same position in its movement in both directions of its oscillating path, at or near point A on the path diagram of Fig. 38. However, the form holder accelerates and decelerates at different portions of its path due to the normal characteristics of its eccentric drive heretofore described. As a result of such speed variation it is found that, as is desirable, the winding advances occur when the form holder is at, or shortly after it has reversed and started to move away from its 30 path limit positions B and F as shown in Fig. 38 (see also Figs. 3 and 13). At such limit positions, it will be recalled, the ribbon extends from front to back of the form through one notch and that it is in the course of the reverse next movement of the form holder that the ribbon is to be drawn from back to front through the next notch of the form.

35 An indexing cam follower pin 183 shown in Figs. 20 and 27 coacts with the steps of cam drum CD. The pin projects downwardly from base 140 of feed carriage FC and the upper portion thereof is housed in vertical bore 184 of such base. Integral with bottom plate 185 which closes the lower end of the bore is a cylindrical sleeve 186 extending upwardly in the bore and in which is secured a bushing 187. A spring 188 surrounding the upper portion of the pin in the sleeve seats against the bushing and acts at its lower end against a flange on the pin. The pin is slidable upwardly under compression of the spring. This permits the pin, after reaching bottom cam step 182 at the end of a winding operation and 40 when the advance shift assembly is moved reversely back

to its starting position while the drum is stationary to ride against surface 189 and thence up ramp 190 and lengthwise along the outer surface of the drum until the pin reaches the top step 180, where it is projected into engagement with such step.

A ring 191 extends around cam drum CD adjacent cam step 180 containing a cam 192 aligned with bottom step 182. Riding against the ring is a spring-pressed actuating rod 193. When the rod is engaged by cam 192 it opens stop switch SS to terminate the drive of the cam drum which is now to be described.

Wind advance assembly control and drive

Cam drum CD is keyed to a drive sleeve 200 on shaft 103 driven from motor EM. The sleeve is free on the shaft and its ends are journalled by bearings supported by trunnions 201 and 202.

Referring to Figs. 23 and 29 in connection with Figs. 20 and 27, sleeve 200 and the cam drum are driven by shaft 103 through a reduction gearing. Fixed to the right end of such shaft is a gear 203 driving an intermediate gear 204 on shaft 216 which drives a further gear 205 fixed on shaft 206. Shafts 216 and 206 are journalled by bearings in intermediate casing wall 207 and right end wall 208.

The gear train just described drives beveled miter gear 209 on shaft 206, which in turn drives beveled miter gear 210 on cross shaft 211 journalled by bearings supported by casing front wall 212 and trunnion 213. The miter gears drive a small worm gear 214 fixed on shaft 211 and meshing with a large profiled gear 215 keyed to cam drum drive sleeve 200.

As already mentioned this drive from shaft 103 should turn the cam drum one revolution for each ten complete oscillating cycles of the form holder which has its separate eccentric drive from shaft 103.

Cam drum CD merely controls the shift of the ribbon advance assembly. Actuation of such assembly is effected by reciprocating pneumatic motor PM connected by piston rod 220 with the feed carriage FC through threaded connection of the right end of such rod with end plate 221 of the carriage base 140.

Motor PM is reversely movable under control of a bleeder type reversing valve RV, shown in Fig. 27. Movable as a unit therein are a pair of valves V-1 and V-2 and oppositely acting valve actuating pistons P-1 and P-2. In the right position of such parts shown air pressure from the supply line is delivered to the right end of motor PM through check valve CV for driving the ribbon shift assembly to the left for ribbon winding advance under control of cam drum CD. The left end of the motor is vented through exhaust port E-2. Magnetic valves MV-1 and MV-2 control actuation of pistons P-1 and P-2. As long as both such valves are closed equal air pressure from the supply line acts on both pistons so that the described valve setting is maintained. Opening of valve MV-2 immediately vents piston P-2 to reduce the pressure thereon through such valve to atmosphere so that the now greater pressure at the right causes piston P-1 to shift the valve and piston unit to the left. In such position valve V-1 cuts off the right end of the motor from the pressure supply and vents the same through exhaust port E-1, slowly through throttle valve TV, check valve CV closing. Valve V-2 closes exhaust port E-2 and supplies pressure to the left end of the motor for returning the ribbon advance assembly to the right to its starting position. If valve MV-1 is now opened piston P-2 will shift the valve and piston assembly to the right to reestablish the valve setting shown and the conditions first described.

One of the characteristics of valve RV is that valves MV-1 and MV-2 after opening to effect a shift may immediately close without causing a further reverse shift of the valve and piston assembly because of the balanced pressure on both pistons P-1 and P-2 when the two magnetic valves are closed.

Ribbon delivery assembly

The pair of coacting grooved and rib ribbon feeding rolls 52 and 53 have been identified as ribbon holder RH because they hold the ribbon for the form holder FH and coact therewith in its oscillating form winding operation. Auxiliary devices are desirably associated with such roll in what has been designated as ribbon delivery assembly RD. The same is generally shown in Figs. 17 to 19 and 20, but is better shown in and to be described in connection with Figs. 30 and 32 and detailed Figs. 33 to 36.

Ribbon delivery assembly RD includes a main supporting block 230 and a rear block 231 hinged thereto. Roll 52 is journalled at the side of block 230 by shaft 232 located interiorly of the block. Roll 53 is similarly journalled at the side of block 231 by shaft 233. The blocks are connected by hinge screw 235 in slightly spaced relation at their opposing vertical walls and the upper inset wall 235 of block 231 in inclined relation to block 230. Through such arrangement the lower part of rear block 231 can hinge backwardly to separate rolls 52 and 53 for easy threading therebetween of ribbon from a supply. The blocks are normally locked together by coaction with notch 236 in block 231 of latch 238 on latch arm 237 mounted by pivot pin 239 in a transverse recess in the upper part of block 230. Pin 240 in vertical bore 242 is yieldingly held against arm 237 by spring 241 to maintain the latch connection but permits the arm to be depressed to release the connection.

The ribbon delivery assembly further includes a ribbon brake or lock device designed to prevent accidental back feed of ribbon from rolls 52 and 53, as during the periods in the winding cycle when there is slack in the ribbon between the rolls and the oscillating form holder FH. Such device, located above the rolls, includes a metal brake block 243 having a smooth operating end face and mounted in recess 244 of block 230. Mounting screw loosely fits brake block 243 to permit adjustment thereof relative to the line of feed of the ribbon. An adjustable set screw 246 in block 230 engages the forward end of block 243 to hold it in any adjusted position.

Opposing and coacting with the rear face of block 243 is a bearinged brake roll 247 having a smooth metal surface and mounted in the forward end of bifurcated arm 248 by pin 249. A side housing 250 on rear block 231 has a horizontal channel (Figs. 32 and 35) loosely receiving the inner side of arm 248. Wall portion 253 of the housing outwardly of the channel is embraced by the bifurcated arm (Fig. 36) and mounts the arm for limited pivotal and lengthwise movement by a pivot pin 254 which has a loose connection with a slot in the wall portion.

Side housing 250 has a front end part 252 having a downwardly and inwardly inclined end cam face coactive with brake roll 247. Leaf spring 255 mounted by a frame arm 256 (Fig. 32) secured to block 230 urges the rear bifurcated arm 248 downwardly and forwardly. Brake roll 247 is thereby held against the cam face of part 252 and maintained in contact with the ribbon. Flange 257 on spring 255 prevents rearward displacement of arm 248 and assists in maintaining such relationship.

The feed of ribbon downwardly between the roll and brake block prevents any braking effect. However, if the ribbon starts to back feed upwardly, spring 255 causes brake roll 247 to ride up on the cam face to draw the roll and its loosely mounted arm 237 forwardly to grip the ribbon against brake block 243. Such braking action is released by further normal downward feed movement of the ribbon, which urges the brake roll downwardly and rearwardly along the cam surface.

Located upwardly of the ribbon brake device is a ball bearing ribbon feed eyelet 258 mounted by arm 259 on block 230 adapted to maintain alignment of the ribbon with the brake device. Since the threading of ribbon therethrough is simple the eyelet is not separable. However it will be apparent that when lock 231 is hinged rearwardly the parts of the brake device are separated for

easy threading of ribbon therethrough as well as through rolls 52 and 53. Such a threading operation requires only a slight spacing of these parts. Accordingly, limit stop 260 may be mounted on block 230 to limit the rearward hinging movement of a block 231.

The whole ribbon delivery assembly is mounted through block 230 on supporting arm 145 of feed carriage FC and moves as a unit with the carriage and ribbon guides, RG and RG' lengthwise of the casing for winding advance of the ribbon along a form being wound on form holder FH. Likewise, at the end of a form winding operation it is returned with the carriage to starting position.

Ribbon supply

Ribbon can conveniently be supplied to the machine from any suitable source, such as a ribbon supply roll SU. Because of the rather jerking nature of the ribbon feed due to the oscillating wind of the form holder, it is desirable to provide ribbon slack and take up mechanism between the supply and the ribbon delivery unit. Such mechanism in the present machine is mounted upon a framing mounted for longitudinal travel with feed carriage FC.

As shown in Figs. 17, 18 and 19 the framing includes a horizontal angular arm 270 secured to feed carriage FC. Projecting upwardly from the outer end of such arm is an angle iron 271. Supported at the top of the latter is a similar angle iron 272. Extending upwardly from the outer end of the latter is an arm 273 which supports a horizontal further arm 274. Bracing such framework is an angular arm 275 secured to the feed housing and connecting arm 274 and earlier mentioned arm 256 secured to block 230 of the ribbon delivery assembly connecting at its upper end with the upper end of angle iron 271.

A grooved ribbon feed roll 276 is mounted upon arm 277 pivoted at its upper end to arm 274 and tensioned rearwardly by a spring 278. The ribbon from supply roll SU passes upwardly over roll 276 to roll 279 mounted on arm 274 and thence rearwardly to a second grooved roll 280 mounted on arm 281 pivoted to frame 273 and tensioned downwardly by spring 282 supported by a further arm 283. From roll 282 the ribbon passes to a further grooved roll 279 mounted on the forward end of arm 274 in vertical alinement with the ribbon delivery unit RD. Through such arrangement, and particularly by reason of the ability of arms 277 and 281 to swing against the tension of their springs, a variable slack is maintained in the ribbon at all times and jerky motion of the ribbon over the winding action of the form holder is not transmitted back to supply roll SU.

Automatic control circuit

An automatic control circuit may be provided for the machine which permits manual starting at the beginning of a winding operation. Continuous winding until completed, followed by resetting of the machine to starting position and then stopping thereof for withdrawal of a wound heating element and insertion of a new heating element form for the next winding operation.

Such a circuit is shown in Fig. 39. The reversing valve RV controlling pneumatic motor PM and magnetic valves MV-1 and MV-2 are shown in Fig. 27 and have already been generally described. An electric control circuit is provided for selectively energizing the magnetic valves including a pair of normally open limit switches LS-1 and LS-2 arranged to be actuated by the feed housing (Fig. 27) on a switch actuating device SA (Fig. 39) thereon at the opposite limits of lengthwise travel of the feed carriage. Closing of limit switch LS-1 energizes magnetic valve MV-1. Closing of switch LS-2 energizes a normally open delayed closing (2 seconds) magnetic switch DS which gives delayed actuation to magnetic switch MV-2.

In the air supply circuit for motor PM are several pressure regulating valves PR for regulating the air supply to motor PM. A normally open pressure switch PS con-

trols the further electric circuit now to be described and maintains such circuit open except when air pressure is available for operation of motor PM.

The electric circuit last mentioned controls motor EM which drives form holder FH in its oscillating winding operation and which further drives cam drum CD controlling the feed advance of the wind advance assembly by motor PM. Such circuit includes a normally open magnetic switch MS which closes to energize motor EM and a magnetic brake MB thereon. The latter is desirable to promote quick stopping of the motor but does not interfere with normal operation. Controlling switch MS is a normally open manual hand switch HS. In parallel with such switch is normally closed automatic magnetic stop switch SS previously referred to as being adapted to be actuated through rod 193 by cam 192 on the cam drum CD. The function of such switch will be further described hereafter. If hand switch HS is closed too briefly, magnetic switch MS may be accidentally deenergized to stop motor EM. To prevent this a further magnetic switch TS is provided in parallel with manual switch HS. Such switch is energized by switch MS simultaneously with the motor. Such switch is of a type which after being energized will automatically open after a short time delay (2 seconds). Switch TS is in parallel with switch HS. A further emergency switch XS is provided for stopping motor EM and the entire operation of the machine when necessary.

Operation

A form EH for an electric heating element is locked in the form holder FH by moving locking bar 70 to locked position by lever 92. The end of ribbon R is drawn manually from front to back through the first notch in the then lower right side edge of the form and up forwardly through a notch provided in the end of the form (Fig. 30) and the ribbon is then caught and anchored under finger 71.

The main pressure switch PR in the pressure supply line of pneumatic motor PM is opened, this resulting in closing of pressure-responsive switch PS in the electrical circuit of motor EM. The various parts will be in the position as shown in Fig. 39.

Switch SS is closed manually, energizing magnetic switch MS to start motor EM. At this time automatic stop switch is held open by engagement of rod 193 with cam 192 on cam drum CD. Closing of switch MS energizes self-opening magnetic switch TS, which closes for two seconds to give the cam drum time to start rotation and release rod 193 to permit switch SS to close to maintain switch MS energized and closed, avoiding accidental breaking of the circuit to the latter if hand switch HS is released too quickly before switch SS has had time to close. Self-opening of switch TS after two seconds does not disturb the circuit once switch SS has closed and switch TS must be opened so switch SS will be able to control the circuit at a later operating stage.

At starting time both magnetic valves MV-1 and MV-2 are closed, valve RV is in its right setting, as in Fig. 27, and pressure is being delivered to right end of pneumatic motor PM. Cam follower pin 183 is then on top cam step 180, preventing motor PM from advancing feed carriage FC until motor EM starts rotating cam drum CD.

The start of motor EM starts the oscillating wind of ribbon by form holder FH on form EH, and, simultaneously, starts rotation of cam drum CD. Under actuation of motor PM the feed carriage is advanced intermittently, step by step, under control of the rotating cam drum to shift ribbon guides RG and RG', ribbon holder RH and the rest of ribbon delivery assembly RD and the ribbon supply pulley frame, and therewith the ribbon, lengthwise of the form holder one form notch at a time in synchronism with the oscillating winding of the form holder.

Twenty windings of ribbon of varying spacing have

been placed on form EH, completing the operation, upon the feed carriage FC having been advanced by motor PM to bring follower pin 183 to bottom step 182 of the cam drum. At this time the feed carriage causes actuator SA to close limit switch LS-2 and energize delayed closing switch DS. This delays change in the pressure circuit to motor PM until final rotation of the cam drum CD has caused cam 192 to actuate rod 193 to open stop switch SS. Opening of switch SS deenergizes and opens magnetic switch MS to stop motor EM and terminate the winding operation. The magnetic motor brake MB which has been energized in released position is deenergized with the opening of the motor circuit and its braking action overcomes motor momentum and assures quick stopping of motor EM.

Closing of switch DS, after a two second delay, energizes magnetic valve MV-2 to open and cause valve RV to shift from its right to left setting to supply pressure to the left side of motor PM to reversely move feed carriage FC back to its starting position, while the right side of the motor vents slowly under control of throttle valve TC to slow the speed of the carriage and prevent shock thereof upon reaching its starting end. During this return movement follower pin rides up ramp 190 on to the cam drum surface and finally drops beyond top cam step 180.

On its return to its starting end carriage FC is caused to go a fraction of an inch beyond its normal starting position so as to close limit switch LS-1. Such switch then energizes magnetic valve MV-1 to open to effect resetting of valve RV from left to right. The left side of motor PM is thereby deprived of pressure and vented, and the return movement of carriage FC is stopped. Simultaneously, pressure is supplied to the right side of the motor to move it reversely in its advance direction a fraction of an inch, until pin 183 stops against cam step 180, so that limit switch LS-1 can again open to deenergize and close valve MV-1. Such closing leaves the setting of valve RV undisturbed so that pressure is available to the right side of motor PM for the start of a new winding operation.

The fully wound heating element form F is now withdrawn from form holder FH after release of locking bar 70 by actuating lever 92. The machine is ready for a new winding operation which is also initiated merely by closing hand switch HS.

It will be evident that the present new winding method provides for efficient production of flat electric heating elements with a single heating face and overcomes the many difficulties of previous laborious hand methods. The method is capable of modification, as has been pointed out, and the same is advantageous in its adaptability to both manual and power employment.

It will also be evident that the fully mechanical machine for practice of the method represents innovations in mechanical wire winding peculiar to the particular type of flat coil which the machine produces. The machine is flexible in that it can be adapted to winding the flat coils with any desired spacing of wire windings and of any desired size, whether for electric toasters or for other uses. The formation of the cam drum can be changed to suit requirements. The basic principles of the machine can be adapted to a variety of equivalent embodiments.

Both the method and machine have been described for the use of ribbon wire. Because of its flat form ribbon wire presents particular problems in handling. Also metal resistance ribbon is most commonly employed in practice because of its thermal properties. It will be apparent, however, that the new method and machine are adapted to winding flat coils with wire of circular or other shape. At the same time, it is also pointed out that the control of the ribbon to prevent undesired twisting and the provision of a practical method and means for developing controlled, localized twists at the anchoring

notches of a mica or other flat insulating supporting form for the production of the heating element disclosed and claimed in copending application Serial No. 185,877, filed September 20, 1950, now Patent 2,659,800, issued November 17, 1953, of Waldo H. Zander, afford advantages in the use of ribbon wire not heretofore realized.

We claim:

1. The method of winding a flat heating element on a flat form having notches spaced along opposing edges which comprises oscillating about an axis between the notched edges of the form one relative to the other the notched form and a wire feeding holder to lay successive windings on the front face of the form in opposite directions upon movements in opposite directions in the oscillating path, drawing the wire of one winding under tension from front to back through a notch at one edge of the form to a surplus length beyond the back of the form and in the next movement in the reverse direction first forming a slack loop in said surplus length of wire and then drawing the wire through an adjacent notch from back to front of the form with removal of slack in the loop at the back of the form between said two notches.
2. The method of winding a flat heating element according to claim 1, further including the step of positively guiding the wire into said adjacent notch on the draw from back to front of the form.
3. The method of winding a flat heating element on a flat form having spaced notches along opposing edges which comprises oscillating about an axis between the notched edges of the form one relative to the other the form and a wire ribbon feeding holder to lay successive windings in opposite directions on one face of the form in movements in opposite directions in the oscillating path, drawing the ribbon of one winding from front to back to a notch at one edge of the form to a surplus length beyond the back of the form, then reversely drawing the wire upon movement in the opposite direction of the path first to form a slack loop in said surplus length of ribbon and then drawing the slack ribbon through an adjacent notch of the form with tightening of the loop against the back of the form between said adjacent notches and formation of a twist in the loop instant to the reversal in the direction of movement of the ribbon.

4. The method of winding a flat heating element on a flat form having spaced notches along opposing edges which comprises oscillating about an axis between the notched edges of the form one relative to another the notched flat form and a wire feeding holder to lay successive windings in opposite directions on the front face of the form, providing a positive wire guide and locating said guide at a notch of the form and drawing the wire of one winding from front to back through said notch to a surplus length beyond the back of the form, advancing the guide to an adjacent notch of the form and drawing the wire from back to front through said guide and said adjacent notch for the next winding.

5. The method of winding a flat heating element on a flat notched form having spaced notches along opposing edges which comprises oscillating the form about its axis between the notched edges relative to a fixed point of wire feed to lay successive windings on the front face of the form, drawing the wire of one winding from front to back through a notch at one edge of the form, advancing one relative to the other a distance of one notch the form and the point of wire feed and drawing the wire from back to front of the form through the next notch for the next winding.

6. The method of winding a flat heating element on a flat notched form having spaced notches along opposing edges which comprises oscillating the form about its axis between the notched edges relative to a wire feeding holder to lay successive windings on the front face of the form, drawing the wire of one winding from front to back through a notch at one edge of the form, advancing the wire feeding holder into alignment with the next ad-

jacent notch and reversely drawing the wire from back to front through said next notch for the next winding.

7. The method of winding a flat heating element on a flat notched form having spaced notches along opposing edges which comprises oscillating the form about its axis between the notched edges, providing a wire feeding holder outwardly of the oscillating path of the form and providing a wire guide in association with the notched edges of the form, with the wire holder and wire guide in registry with a notch at one edge of the form drawing the wire of one winding from front to back through said notch, advancing the wire holder and wire guide to the next adjacent notch and reversely drawing the wire from front to back through said wire guide and said notch for the next winding.

8. The method of winding a flat heating element on a flat notched form which comprises oscillating about an axis between the notched edges of the form one relative to the other the form and a wire feeding holder to lay successive windings on the front face of the form, drawing the wire of one winding from front to back through a notch at one edge of the form to a surplus length beyond the back of the form and then reversely drawing the surplus wire through an adjacent notch from front to back of the form for the next winding while holding the wire against back feed at the wire-feeding holder.

9. A flat coil winding machine comprising a form holder adapted to support a flat form for a coil, a wire feeding holder, two wire guides located adjacent the positions of the opposite edges of a flat form supported by the form holder, actuating means for oscillating one of said holders in an arcuate path relative to the other about the axis of the form holder, means for holding said guides against oscillation relative to said form holder for thereby maintaining said guides at said position of the opposite edges of said form on said form holder during such oscillation, means for intermittently shifting step by step one of said holders relative to the other holder along said axis of the form holder in timed relation with the oscillation of the oscillating holder and means for holding said guides against axial motion relative to said wire feeding holder for thereby maintaining said guides in alignment with said wire feeding holder during said step-by-step axial shifting.

10. A flat coil winding machine comprising a form holder adapted to support a flat form for a coil, a wire feeding holder, two wire guides located adjacent the positions of the opposite edges of a form supported by the form holder, actuating means for oscillating the form holder and the wire guides in an arcuate path about the axis of the form holder and means for intermittently shifting step by step one of said holders and the wire guides relative to the other holder along said axis of the form holder in timed relation with the oscillation of the form holder and the wire guides, and means for holding said guides against axial motion relative to said wire feeding holder and for maintaining said guides in alignment with said wire feeding holder during said step-by-step axial shifting.

11. A flat coil winding machine comprising a form holder adapted to support a flat form for a coil, a wire feeding holder, two wire guides located adjacent the positions of the opposite edges of a form supported by the form holder, actuating means for oscillating the form holder and the wire guides in an arcuate path about the axis of the form holder and means for intermittently shifting step by step the wire holder and the wire guides along said axis of the form holder in timed relation with the oscillation of the form holder and the wire guides.

12. A flat coil winding machine comprising a form holder adapted to support a flat form for a coil, a wire feeding holder, actuating means for oscillating one of said holders in an arcuate path relative to the other about the axis of the form holder, a reciprocating pneumatic motor operative to shift one of the holders relative to the

other along said axis of the form holder, a variable stop for said one holder including rotary stepped cam mechanism for progressively limiting the movement in one direction along said axis and means for rotating the cam operative to cause the pneumatic motor to shift said one holder intermittently, progressively, and step by step in said one direction in timed relation with the oscillation of the oscillating holder.

13. A flat coil winding machine comprising a form holder adapted to support a flat form for a coil, a wire feeding holder adapted to feed wire to the form holder, means for applying tension to a wire fed by said wire feeding holder, a wire brake device for preventing reverse feed of wire by the wire feeding holder, actuating means for oscillating one of said holders relative to the other in an arcuate path exceeding 180° about the axis of the form holder and means for intermittently shifting step by step one of said holders relative to the other holder in timed relation with oscillation of the oscillating holder.

14. A flat coil winding machine comprising a form holder for supporting a flat form for a coil, said form holder being flat for supporting a flat coil form with opposite margins of the form outwardly of the form holder, a pair of wire guides each in position for slideably embracing one of the two opposite margins of a form supported by the form holder, said wire guides having wire guiding channels in position to communicate with said form margins, a wire feeding holder for delivering wire to the wire guides, actuating means for oscillating one of said holders relative to the other in an arcuate path exceeding 180° about the axis of the form holder and means for intermittently shifting step by step one of said form holders and said wire guides in the direction of the axis of the form holder in timed relation with the oscillation of the oscillating holder.

15. A flat coil winding machine comprising a form holder for supporting a flat form for a coil, said form holder comprising a plate for supporting such a coil form with opposite margins of the form outwardly of the form holder, a pair of wire guides each in position for slidably embracing one of the two opposite margins of a form supported by the form holder, carriage means supporting the wire guides for turning movement about the axis of the form holder and for movement along the axis of the form, a wire holder for delivering wire to the wire guides, actuating means for oscillating the form holder and the wire guides in an arcuate path about the axis of the form and means for intermittently shifting said carriage means lengthwise of the axis of the form in timed relation with the oscillation of the form holder and the wire guides.

16. A flat heating coil winding machine according to claim 15 wherein the carriage means for wire guides includes rolling contact means making rolling supporting contact with the form holder.

17. A flat-coil winding machine comprising a form holder for supporting a flat form for a coil with the opposite margins of the form projecting beyond the form holder on opposite sides of the form-holder axis, said form holder being mounted for turning movement about said axis, a pair of wire guides each positioned and arranged to slideably embrace a separate one of two opposite projecting margins of a form so supported on said form holder, each of said wire guides having a sloping channel extending transverse said axis and having also a recess below said channel and communicating therewith, through which wire is delivered to the form margins, and a wire feeding holder for delivering wire to the channels of said guides.

18. A flat coil winding machine according to claim 17 wherein the wire guides are formed with wire receiving grooves extending lengthwise of the form holder axis adapted to face the back of the margins of a coil form.

19. A flat coil form winding machine according to claim 18 wherein the wire guides each has a sloping ele-

ment defining one side of the wire channel, and wherein the recess underlying the channel underlies said sloping elements and has an open end facing the form margin whereby wire in the course of winding through the wire guide may locate under the sloping element.

20. A flat coil winding machine comprising a form holder for supporting a flat form for a coil, a drive shaft operatively connected with the form holder, mounting means supporting the form holder and shaft, actuating means for oscillating the shaft to turn the form holder through an arcuate path, a carriage mounted for movement in a path lengthwise of said shaft, a wire feeding holder supported by said carriage for feeding wire to the form holder, a yoke mounted on said carriage for movement therewith and for independent turning movement, said yoke having arms extending on opposite sides of the form holder, a pair of wire guides mounted on the arms of the yoke and overlying the form holder, a reciprocating pneumatic motor for reversely moving said carriage for moving the wire holder and wire guides, a rotary stepped cam drum, a cam follower on said carriage co-active with the drum to cause the pneumatic motor to advance the carriage intermittently step by step in timed relation to the oscillation of the form holder.

21. A flat coil winding machine according to claim 20 further including control means for the pneumatic motor operative after step by step advance of the carriage in one direction of its path to cause said motor to move said carriage continuously to the opposite end of its path.

22. A flat coil winding machine according to claim 20 where the actuating means for the form holder includes a rotary electric motor, and further including means for rotating the cam drum by said rotary motor, a control pneumatic circuit for reversing the pneumatic circuit and a control electric circuit for said electric circuit and circuit control devices for both circuits becoming operative upon the carriage reaching the limit of its step by step advance to stop the electric motor and cause the pneumatic motor to return the carriage to the other end of its path.

23. The method of claim 1 wherein there is included the operation of holding said one winding in place while forming said slack loop and drawing the wire through said adjacent notch.

24. The method of claim 1 wherein the wire when drawn into said first notch is bent over the edge of the form sufficiently to deform said wire.

25. The method of claim 5 wherein the angle of oscillation between said form and wire-feeding holder exceeds 180°.

26. The method of winding a strand on a flat form which comprises, laying the strand from front to back of the form through a notch at the edge thereof, drawing a surplus length of strand behind said form, leading the strand forward to form a slack loop in said surplus length, laying the strand from back to front through a second notch adjacent to the first, and drawing said strand tight to contract said loop against the back of the form between the two notches.

27. The method of claim 26 wherein said strand is ribbon-like and wherein the strand is held substantially against rotation about its own longitudinal axis.

28. The method of forming a winding on one face of a flat form which comprises fastening a strand to the form, pulling the strand and rotating one of said strand and form for laying a span across one face of said form and drawing said strand over an edge, holding the span in place, slackening and looping the overhanging part of the strand, laying the slack loop around a projection on said form and pulling the strand tight.

29. The method of claim 28 wherein there is included the step of moving a guide into place for guiding said loop into place around said projection.

30. The method of claim 28 wherein the step of holding

the span in place is accomplished by placing a member over it for holding the strand between said member and the form.

31. The method of claim 28 wherein the form is rotated in one direction for laying said span across it and for drawing said strand over an edge, and rotated in another direction for slackening and looping said strand, laying the loop, and pulling the strand tight.

32. The method of claim 31 wherein said two directions of rotation are opposite, said rotation continues in each direction through more than 180° for laying successive, substantially-parallel spans across one face of said form.

33. The method of forming a winding on one face of a flat form which comprises fastening a strand to the form, pulling the strand and rotating one of said strand and form for laying a span across one face of said form and bending said strand over an edge of said form, slackening and looping the overhanging part of said strand, laying the slack loop around a projection on said form, and pulling the strand tight.

34. The method of winding a flat heating element on the front face of a flat form having notches spaced along two opposite edges, which comprises, oscillating about an axis between said notched edges of the form one relative to the other, the notched form and a wire feeding holder, drawing the wire under tension from front to back through a notch at one of said edges of the form, moving a wire guide into place behind an adjacent notch for guiding the wire thereinto, leading the wire from back to front through said guide and said adjacent notch.

35. The method of winding a strand on a flat form which comprises laying the strand from front to back of the form at one side of a projection thereon, drawing a surplus length of said strand beyond said projection, leading the strand forward to form a slack loop in said surplus length, pulling the loop tight and guiding the loop over said projection.

36. The method of winding a strand on a flat form which comprises laying the strand from front to back of the form at one side of a projection thereon, moving a guide into position behind said projection, carrying said strand around said guide and from back to front past said projection and pulling the loop tight against said guide for transferring said loop from said guide to said projection.

37. The method of winding a strand on a notched flat form which comprises laying the strand from front to back of the form through a notch at the edge thereof, then covering said notch, laying the strand forward through an adjacent notch and pulling the strand.

38. A flat-coil winding machine comprising a form holder for holding a flat form for a coil, said form holder being rotatable about an axis approximately parallel to the form, a wire guide cooperable with said form holder for guiding a wire wound on a form on said holder, a support for said wire guide rotatable about an axis approximately parallel to the first axis, and means connecting said form support and guide support constraining them to rotate together.

39. The combination of claim 38 wherein there is included driving means for rotating one of said supports and through it, the other one, and wherein there is included means for moving said other support approximately in the direction of said axis for thereby moving it relative to said one support.

40. A flat-coil winding machine comprising a form holder for holding a flat form for a coil, a pair of wire guides, means supporting one of said guides at the position of an edge of such form on said holder and the other guide at the position of an opposite edge generally parallel to the first edge, said form holder being rotatable about an axis between and approximately parallel to said edges of a form, said guide support being rotatable about a similar axis, and connecting means between said form holder and guide support for constraining them to rotate to-

gether, said connecting means applying the forces of constraint to said guide support close to said wire guides.

41. The combination of claim 40 wherein said form holder and guide support have relative movement along said axis and wherein said connecting means include tracks on said form holder and rollers on said guide support.

42. A flat-coil winding machine comprising a form holder for holding a flat form for a coil, a wire feeding holder, oscillating means carrying at least one of said holders for laying a strand of wire from said holder from front to back of said form through a notch at an edge thereof, a wire guide supported relative to said form holder to lie back of said form, means preventing movement between said wire guide and form holder in the direction of oscillation of said oscillating means, said guide having a wire guiding surface inclined to said direction of oscillation and terminating in a wire-discharging edge, and actuating means for moving said wire-discharging edge of said guide across said notch in timed relation to the operation of said oscillating means.

43. The winding machine of claim 42 wherein said wire guide is tapered, being smallest at its discharge edge and wherein said guide is so oriented with respect to its direction of motion that said wire-discharge edge is on the side that leads as said guide is moved to carry said edge across the notch of the form.

44. The method of winding a flat heating element on a flat form having notches spaced along opposing edges which comprises oscillating about an axis approximately parallel to the notched edges of the form, one relative to the other, the notched form and a wire feeding holder to lay successive windings on the front face of the form in opposite directions upon movements in opposite directions in the oscillating path, drawing the wire of one winding under tension from front to back through a notch at one edge of the form to a surplus length beyond the back of the form and in the next movement in the reverse direction, first forming a slack loop in said surplus length of wire and then drawing the wire through an adjacent notch from back to front of the form with removal of slack in the loop at the back of the form between said two notches.

45. The method of claim 44 wherein there is included the operation of holding said one winding in place while

forming said slack loop and drawing the wire through said adjacent notch.

46. The method of winding a flat heating element on a flat notched form having spaced notches along opposing edges which comprises oscillating the form about an axis approximately parallel to said notched edges of the form, providing a wire feeding holder outwardly of the oscillating path of the form and providing a wire guide in association with the notched edges of the form, with the wire holder and wire guide in registry with a notch at one edge of the form, drawing the wire of one winding from front to back through said notch, advancing the wire holder and wire guide to the next adjacent notch and reversely drawing the wire from front to back through said wire guide and said notch for the next winding.

47. A flat coil winding machine comprising a form holder for supporting a flat form for a coil with the opposite margins of the form projecting beyond the form holder on opposite sides of the form-holder center, a pair of wire guides each positioned and arranged to slideably embrace a separate one of the two opposed projecting margins of a form so supported on said form holder, each of said wire guides having a sloping channel extending transverse the margin of the form and having also a recess below said channel and communicating therewith through which wire is delivered to the form margins, a wire-feeding holder for delivering wire to the channels of said guides, and means for oscillating one of said holders relative to the other about an axis substantially parallel to said form margins.
